UNITED STATES PATENT OFFICE.

WILLIAM H. MALOY, OF SUFFERN, NEW YORK, ASSIGNOR TO EDWARD H. FALLOWS,
OF NEW YORK, N. Y.

BACK FOR BRAKE-SHOES.

1,019,812.

Specification of Letters Patent. Patented Mar. 12, 1912.

Application filed October 23, 1911. Serial No. 656,212.

To all whom it may concern:

Be it known that I, WILLIAM H. MALOY, a citizen of the United States, and a resident of Suffern, in the county of Rockland and 5 State of New York, have made and invented certain new and useful Improvements in Backs for Brake-Shoes, of which the following is a specification.

My invention relates to steel backs for 10 brake shoes formed from a single piece of metal by bending and shaping a suitable blank, the same being designed to be placed in a mold, in position to become embedded in the rear surface or back of a brake shoe, 15 as molten metal is poured thereinto, the object thereof being to provide an improved steel back of the type referred to having features of construction and advantage as hereinafter disclosed, and to provide a 20 blank from which such a steel back may be formed by suitable bending and shaping operations, all as hereinafter defined in the concluding claims.

My improved steel back and blank are 25 illustrated in the drawing accompanying and forming a part of this application wherein:

Figure 1 is a view illustrating the manner in which blanks for the backs are cut from 30 a sheet or plate of wrought metal such as mild steel; Fig. 2 is a view showing a section cut from the plate shown in Fig. 1, and which section may be divided to form several back blanks; Fig. 3 is a view showing 35 a single back blank, and, Fig. 4 is a view showing in perspective a steel back formed from the blank shown in Fig. 3.

The blank from which my improved steel back is formed comprises oblong side portions 5—5, of approximate rectangular form 40 connected with one another by a cross piece 6 extending between the sides and located at or about their middle as shown. This cross piece is bent and forced out of the plane of the sides to provide a projecting loop or lug 7 in the completed back shown in Fig. 4, the sides or ends 8 of which are about at right angles to the plane of the sides as shown, the sides themselves being 45 curved as shown to conform, approximately, to the curvature of the brake shoe in which the back is embedded. The loop 7 serves as a means for attaching the brake shoe to a 50 brake head by means of a key, as will be understood.

The shaping operation above referred to is performed upon the blank shown in Fig. 3 by means of suitable dies, one effect of bending or forcing the cross piece 6 out of the plane of the sides 5 being to draw the 60 sides toward one another, so that the side portions 9—9 of the finished back lie closer to one another than the sides of the blank from which the back is formed.

In my invention I provide recesses adjacent the ends of the cross piece 6 where it joins the sides 5, as shown at 10, these recesses extending from the inner edge of the sides into and part way across the same, the form of which recesses, while shown as 65 semi-circular may be varied as desired.

The provision of recesses at the place where the edges of the sides 5 and cross piece 6 meet prevents the formation of 70 cracks, or undue straining of the metal as the cross piece is bent to form the loop or lug 7, and results in a construction in which the bases of the ends 8 are brought into a position between the edges and near the 75 middle of the sides, and whereby the ends 80 of the lug do not spring from the inner edges of the sides of the back as is the case in former types of steel backs. More space 85 is also secured between the lower portion of the ends 8 of the lug, the side portions 9 of the finished back are brought closer together 90 than were such recesses not provided, and a greater length of cross piece from which to form the lug is secured than in former blanks.

The blanks from which the steel back is 95 formed may be produced in any way. They are, however, preferably cut from a long narrow strip of sheet metal with a minimum waste of material in accordance with the method of cutting blanks for brake shoe backs disclosed and claimed in the patent to Harry Jones, No. 995,011, June 13th, 1911. Fig. 1 shows such a strip, and the lines appearing thereupon indicate the path along 100 which the sheet is cut, as by means of suitable cutting dies. Fig. 2 shows a section cut from the sheet, which is subsequently divided to form individual blanks such as 105 are shown in Fig. 3.

In forming blanks in accordance with the method above referred to, projections 11, corresponding in outline with the recesses 10, are secured at the ends of the side portions 5, which projections serve to anchor 110

the ends of the sides 9 of the finished back more firmly in the back of the cast metal body of the shoe as the same is formed, and to prevent the end portions of the body of the shoe from shifting longitudinally and becoming detached, should the shoe be cracked or broken in use, it being not uncommon in practice for the cast metal body portion of a brake shoe to be cracked or broken transversely, in which event, if the parts of the shoe be not securely held or bound together, the end portions are liable to become detached and fall from the shoe, and result in serious accident.

15 Having thus described and explained my invention, I claim and desire to secure by Letters Patent:—

1. A blank for a back for a brake shoe having two side portions and a cross-piece 20 extending between them whereby they are joined together, said blank having recesses adjacent the ends of said cross-piece and extending into said sides.

2. A blank for a back for a brake shoe 25 having two similar side portions and a cross-piece extending between them whereby they are joined together, said blank having recesses adjacent the ends of said cross-piece and extending into said sides, and projections corresponding in outline with said recesses at the ends of said side portions.

3. A blank for a back for a brake shoe having two side portions and a cross-piece 35 extending between them whereby they are joined together, said blank having two recesses adjacent one end of the cross-piece and located one upon either side of said cross-piece and extending into one of the sides aforesaid of said blank.

40 4. A back to be embedded in a brake shoe,

the same comprising two side portions and a projecting loop or lug formed integrally with said sides and whereby they are connected with one another, the bases of the end portions of said lug joining with the side portions of said blank between the side edges thereof.

5. A back to be embedded in a brake shoe, the same being formed from a single piece of metal and comprising two side portions 50 and a projecting loop or lug extending from one of said sides to the other, said lug springing from the middle portion of said sides and midway between the side edges thereof, the base portions of the ends of 55 said lug extending longitudinally of the shoe.

6. A back to be embedded in a brake shoe, the same having two parallel side portions 60 separate from one another and a projecting loop located at the middle portion of said sides whereby they are joined together, and projecting lugs lying in the plane of said sides and located at the ends of said side portions.

7. A back to be embedded in a brake shoe, the same having substantially parallel sides 70 separate from one another and a projecting loop located at the middle portion of said sides whereby they are joined together, and lugs at the ends of said side portions, said lugs lying in the plane of said sides and extending toward one another.

Signed at Suffern, in the county of Rockland and State of New York, this 17th day 75 of October, A. D. 1911.

WILLIAM H. MALOY.
